point 38 to limit the closing movement of said prong. To insure an easy entrance for prong 28 into sheath the two walls of the sheath are formed downwardly converging. The side walls 20 and 22 of housing 12 have portions indented at 42 to permit of free movement of spring 36 therebetween however these side walls are somewhat flexible whereby the operator by pressing against the side walls can exert sufficient pressure against prong 28 to prevent a closing movement of prong 28 while prong 28 is being inserted into the fabric of the infant's garment. These side walls are conveniently located so that they may be easily engaged by the operator during the pinning operation.

Referring to spring 36 as shown in Fig. 1 it will be noted that it is only slightly offset from the dead center of its position causing only relative slight end pressure to urge the prong to closed position, also the turned down stop 26 of top wall 24 will engage the opening prong 28 to prevent it from moving spring 36 to the dead center. When so positioned the closing urge of the prong 28 will be easily overcome by the operator as he moves offsets 42 against spring 36.

It is apparent that this safety pin is so constructed that the prong is constantly urged to the locked position relative to the keeper whereby the prong point at rest is always completely protected by a suitable covering, which will eliminate the possibility of a child swallowing an open safety pin.

Referring to the mode form shown in Fig. 5 it will be noted that the operation and structure of this safety pin is substantially the same as that shown in Fig. 1. This pin has a bar 50 provided at its one end with a keeper 52 and at its other end with a prong 54 mounted for pivoted movement in the side walls of housing 56 by trunnions 58. Prong 54 is pivoted intermediate the ends to present a sharpened garment engaging section 60 and an operating lever end portion 62. Mounted in housing 56 on a fixed stop 64 is a spiral spring 66 having its free end pivoted to lever 62 to urge section 60 toward the closed position. It will be noted when section 60 is manually moved to the open position the lever 62 will be positioned substantially parallel with the extended end of spring 66 thus its urge to close the prong is at a maximum when it rests against stop 68. The action of spring 66 as it rewinds to move prong 54 to the closed position is of sufficient force to completely lock the safety pin. Offset 70 is so related to prong 54 that when the operator presses on side walls of housing 56 sufficient pressure will be exerted against prong 54 to secure it against closing movement, while the pointed section 60 is being inserted in the infant's garment.

The modified form shown in Fig. 7 is likewise similar to the form shown in Fig. 1 and comprises a bar 72 having a keeper 74 at one of its ends and a housing 76 at its other end. Pivotaly mounted in housing 76 is a prong 78 pivoted intermediate its ends on trunnions 80 pivoted in the side walls of housing 76 to present a sharpened prong 82 suitable for insertion through the fabric of the infant's garment and a rearwardly protruding arm 84 to which one leg of a U-shape spring 86 is pivoted at 87 for compression action against a post 88 to which the other leg of spring 86 is pivoted. It will be noted that when prong 78 is in the opened position shown in solid lines in Fig. 7, trunnions 80, pivot 87 and post 88 are near alignment spring 86 is substantially fully com-

pressed and ready to expand and move prong 78 to the closed position. Stop 90 serves to contact prong 78 to prevent the aligned parts to move past dead center, thus insuring the return of prong 78 to the closed position. If the operator desires to hold prong 78 in the open position during the pinning operation he simply presses against the side walls of housings 76 to pinch arm 84 between the offsets 86 formed in said side walls. After the pinning operation is completed the operator releases his grip on said side walls and the tongue immediately moves to the closed position.

The safety pin shown in longitudinal sectional view in Fig. 9 comprises bar 92 having a keeper 94 at its one end and a housing 96 at its other end. Pivotaly mounted intermediate its ends in side walls of housing 96 or trunnions 98 is a spring wire prong 100, having a sharpened prong forward section 102 which serves to penetrate the fabric of a garment and a substantially U-shaped rear end portion 104 having a spring coil 106 at its return bend, with a free end portion 108 formed and positioned to bear against a cam pin 110 fixed to housing 96 so that as prong 100 is moved to the open position as shown in solid lines in Fig. 9 energy will be stored up in spring coil 106 with end 108 sufficient to urge prong 100 to the closed position 25 shown in dotted lines in Fig. 9 when the prong is released. When prong 100 is in the opened position this pin 120, cam 110 and spring prong parts are so relatively positioned that the spring urge tending to close said prong will be at a minimum. If the operator desires to hold prong 100 in the operating position during the garment pinning operator simply presses on the side walls of housing 96 to press the wall offsets 103 against prong portion 104 whereby it is held against closing movement.

The modified form shown in Fig. 11 comprises a bar 112 provided at its one end with a keeper 114 and at its other end with housing 116. A resilient prong 118 pivoted at its inner end on pin 120 mounted in the side walls of housing 116 is offset rearwardly at 122 to present a pair of spaced apart arms 124 and 126 joined together by a spring coil 128. Arm 126 is so arranged relative to arm 124 that as the sharpened end 130 is moved to the opened position as shown in solid lines in Fig. 11 the prong 118 will be energized to snap the end portion 130 of the prong to the closed position and in engagement with the keeper 114. Stop member 132 serves to limit the opening movement of prong 118. By pressing 55 on the side walls of housing 116 when prong 118 is fully opened the prong may be so held between stops 134 to permit easy insertion of 130 into the garment fabric when the pin is inserted the operator releases the side wall of the housing so that the offsets 134 will release the prong and permit it to move to the closed position. When prong 118 is at the open position pin 120 and cam arm 124 and arm 126 will be spread a maximum giving a minimum spring action tending to close the prong 118.

Safety pin shown in Figs. 13 and 14 is very similar to these shown in Figs. 9 and 11 the principal difference being that prong member 140 is semi-floating since its spaced apart spring portions 142 and 144 resiliently engage and float about a post 146 fixed in the side walls of housing 148 disposed at one end of a safety pin back bar 150. The other end portion of bar 150 has a keeper 152 which serves to receive the sharpened end portion 154 of said prong. Spring portions

142 and 144 are joined together in substantially parallel relation by means of a spring coil 156 formed in prong member 140. Coil 156 rides against the inside wall of housing 148 to maintain the prong portions in proper floating position on post 146. A stop 158 formed on housing 148 serves to limit the opening movement of prong 140 to a position wherein the parts are so positioned that a minimum tension is exerted to close the prong to engage keeper 152. The side walls of housing 148 are offset inwardly at 160 whereby during the pinning operation the operator may press inwardly on said side walls to cause offsets 160 to clamp prong section 144 to hold prong portion 154 in the open position. After the pinning operation is completed the operator releases said side walls and the prong member springs to the closed position.

The modified form shown in Figs. 15 and 16 comprises a bar 162 provided at its one end with a keeper 164 and at its other end with a housing 166. A prong member 168 is pivoted intermediate its end on trunnions 170 which are mounted in the side walls of housing 168. Prong 168 is sharpened at its forward end 172 for insertion in a garment and its rear end portion 175 extends rearwardly to bear against the free end portion 174 of a U-shaped spring member 176 which is anchored at 178 to the housing 166. As the prong 168 is moved to the open position prong portion 175 will ride along spring 174 until prong 168 is limited by stop 180 so that spring portion 174 will be exerting a minimum force to close the prong 160. This force will be built up as the prong is moved up to the closed position shown in dotted lines in Fig. 15. Offsets 182 formed in side walls of housing 166 serve to grip prong at 175 to secure prong 168 in the open position during the pinning operation by simply pressing against said side walls.

The modified form shown in Figs. 17 and 18 are quite similar to that shown in Fig. 15 with the exception of slight changes in the shape of the prong and the operating spring. The safety pin comprises a bar 186 having a keeper 188 supported on its one end and a housing 190 on the other end thereof.

The prong 192 is pivoted intermediate its ends by means of trunnions 194 mounted in the side walls of housing 190 the forward end portion 195 of prong 192 is sharpened for easy insertion into a garment, while the rear portion 196 is offset angularly relative to portion 195 to bear against the free end 197 of rearwardly extending spring 198 which is secured to bar 186. As prong 192 is moved to its open position it will contact stop 199 when it has reached a position of slightest urge to close the prong 192. However it will have built up sufficient energy in spring 198 to completely close and latch said prong beneath keeper 188. Offsets 187 formed in side walls of housing 190 are adapted to be manually pushed against end portion 196 of the prong to hold it in the open position during the pinning operation.

Fig. 19 shows a modified form of the safety pin wherein the bar and prong are formed from one continuous piece of spring wire so as to provide sufficient stability to the prong. This combined bar and prong is somewhat similar to the present safety pin made of wire, and differs materially therefrom in view of the fact that it is so constructed that the prong is energized to always

tend to move to the closed position other than to the open position as is the case in the present safety pin. This pin shown in Figs. 19 and 20 comprises a single strand of spring wire 200 coiled intermediate its ends at 202 with its end portions 204 and 206 disposed in substantially parallel relation at one side of said coil. Portion 204 comprises a back or bar for the pin and 206 is a closing prong which is tensioned to always urge

10 the sharp point 208 to a position beneath the keeper 210 formed in the sheath 212 carried by said portion 204.

A bar 214 pivoted by trunnions 216 to wire 204 serves to engage the underside of prong 206 to 15 support it in the open position. A light weight coil spring 220 secured at its one end 222 to wire 204 and with its free end resting against the rear side of bar 214 tends to urge the bar toward its forward position. However prong 206 20 is so formed that it is energized sufficiently to be constantly urged to the closed position against the resistance of spring 220 to engage keeper 210.

From the foregoing description it is apparent that I have presented several forms of self closing safety pins which are well adapted for the purpose intended, and it is quite apparent that many other forms and modifications might be made that might properly fall within the scope of the appended claim.

30 What I claim and desire to secure by Letters Patent is:

A safety pin comprising an elongated body member having a keeper at one end thereof, a spring wire prong one end of which is adapted 35 to engage said keeper and the other end of which has a substantially U-shaped resilient bend formed therein in the plane determined by said body member and prong, one of the legs of said U-bend being pivotally mounted in said body 40 member on a transverse axis, whereby said prong is movable from a closed position in engagement with said keeper to an open position apart from said keeper, and a transversely extending cam pin fixed in said body member and engaging the 45 inner surface of the opposite leg of said U-bend, said pin and said pivot being spaced apart sufficiently that said U-bend is resiliently distended, said pin and pivot being offset longitudinally of 50 said body member whereby said prong is urged resiliently toward the closed position, the closed end of said U-bend being adapted, as said prong is moved manually to the open position, to be moved to a position approaching equidistant spacing from said pivot and said cam pin, where- 55 by the spring force tending to move said prong to the closed position is gradually diminished.
